UNITED STATES PATENT OFFICE.

JOHN ROBINSON AND CLAYTON WEEKS, OF HOBART, NEW YORK.

CAR-COUPLING.

SPECIFICATION forming part of Letters Patent No. 417,368, dated December 17, 1889.

Application filed October 19, 1889. Serial No. 327,557. (No model.)

To all whom it may concern:

Be it known that we, JOHN ROBINSON and CLAYTON WEEKS, citizens of the United States, residing at Hobart, in the county of Delaware 5 and State of New York, have invented certain new and useful Improvements in Car-Couplings; and we do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 The special object of our invention is to construct the draw-head of a car so as to enable cars of different heights to be conveniently coupled together with the same length of link and pin.

20 The invention will first be described in connection with the drawings and then pointed out in the claim.

Figure 1 of the drawings is a front elevation in perspective; Fig. 2, a cross vertical section 25 with the cap removed, and Fig. 3 a horizontal sectional view of the coupler. Fig. 4 is a detail view of the cap.

In the drawings, A represents the draw-head, divided horizontally by the partition a into 30 two link-chambers and provided with the registering-holes a' a' a' for the reception of the coupling-pin D. The outside of the end or mouth of the draw-head, as well as the front of partition a, is beveled to facilitate the entrance of the link C.

S represents a tapering spindle, which enters at the lower side of the draw-head and extends up through it, being held at the upper end by the cap D and set-screw E. The set-screw passes through the cap into a slot s 40 of the spindle, the same allowing the shaft to turn in the quadrant of a circle, or nearly so. On this spindle are arranged fixedly two arms s' s', of which the upper one sustains the pin B until the link pushes it back and up as it 45 enters the draw-head. If the draw-head of the opposite car is high, then the link passes above the partition a, and below it if said draw-head is low.

The cap D has teeth d, and a projection D' 50 has corresponding teeth d', the teeth d d' interlocking, so as to prevent the cap from turning on the draw-head.

Having thus described all that is necessary to a full understanding of our invention, what 55 we claim as new, and desire to protect by Letters Patent, is—

The combination, with the two-armed spindle, of a toothed projection on the draw-head and a toothed cap, as and for the purpose set 60 forth.

In testimony whereof we affix our signatures in presence of two witnesses.

JOHN ROBINSON.
CLAYTON WEEKS.
